PILE HAMMER

Noel Gonine Bell, London, England

Application September 16, 1942, Serial No. 458,590
In Great Britain July 7, 1941

2 Claims. (Cl. 121—30)

This invention relates to the type of pile-driving hammer that comprises a stationary piston, a cylinder reciprocable vertically with respect to the piston to form the hammer striking ram, and a valve associated with the piston to control the admission and exhaust of motive fluid to and from the cylinder as required alternately to raise the cylinder and allow it to fall by gravity.

Pile driving hammers of the aforesaid type have the characteristic that a high proportion of their total weight is in the ram, i. e. the cylinder.

Objects of the invention are, firstly, to provide a pile-driving hammer with the above mentioned characteristic maintained or enhanced and with improved and simplified means for bringing about the automatic operation of the control valve on reciprocation of the cylinder and, secondly, the provision of means for the said purpose such that it is completely protected from damage when the cylinder is at rest in its lower position, i. e. its position when "pitching" piles or transporting the hammer and, thirdly, to provide a construction such that the motive fluid does not exert upward pressure on the stationary element, i. e. the piston (which it is a main object of the invention to make as light as possible), and cause it to bounce on the pile.

Accordingly the invention provides a pile-driving hammer comprising, in combination, a hollow piston having upper and lower vertically extending hollow piston rods, a cylinder reciprocable relatively to the piston to form the hammer striking ram guided by the piston rods, a valve turnable within the hollow piston and having angularly spaced facing members engaging the inner surface of its peripheral wall, the said wall having admission and exhaust ports opening through the said inner surface and leading respectively to the cylinder space above and below the piston, means for supplying motive fluid to the hollow piston through the upper hollow piston rod, and means disposed wholly below the piston to turn the valve automatically on reciprocation of the cylinder alternately to open the said admission ports to the supply of motive fluid and to the said exhaust ports.

Preferably the said means comprises a cam rod situated below the piston and engaging the control valve at its upper end and presenting linearly spaced cam ramps corresponding to admission and exhaust positions of the valve, in combination with at least one member projecting inwards from the cylinder into sliding engagement with the cam rod.

If desired, there may be sets of linearly spaced cam ramps, the spacing of the cam ramps in the said sets being different in order to enable the hammer stroke to be varied according to which set is utilised, that is with which set the member projecting from the cylinder selectively co-acts.

Further, the cam rod may be accommodated in the piston rod below the piston, the piston rod being hollow to accommodate it, and the cam rod having a cam groove (or cam grooves) presenting cam ramps (or sets of cam ramps) as aforesaid, the piston rod also having an axial groove (or grooves) for the passage of the projecting cylinder member into co-acting sliding engagement 15 with the cam groove (or a selected one of the cam grooves).

By way of example a pile driving hammer embodying the aforesaid and other features of the invention is illustrated on the accompanying drawing to which reference will now be made.

Fig. 1 is an elevation of the hammer partly in section.

Fig. 2 represents, on a larger scale, a quarter section through the piston and valve in the plane II—II of Figs. 5 and 6, the valve being in the admission position; all four quadrants are identical.

Fig. 2a is a view similar to Fig. 2 but showing the valve in the "exhaust" position.

Fig. 3 is a sectional top plan of one quarter of the piston in the plane III—III of Figs. 5 and 6.

Fig. 4 is a sectional bottom plan of one quarter of the piston in the plane IV—IV of Figs. 5 and 6.

Fig. 5 represents, in vertical section in the plane V—V of Fig. 2a, half of the piston and valve and shows how the admission ports open to the cylinder space above the piston.

Fig. 6 represents, in vertical section in the plane VI—VI of Fig. 2a, half of the piston and valve and shows how the exhaust ports open to the cylinder space below the piston.

Fig. 7 represents a part section through the hammer in the plane VII—VII of Fig. 1.

Fig. 8 represents a section through the lower piston rod and cam rod of a modification.

Fig. 9 represents an elevation of the cam rod showing the cam groove and ramps.

Referring now in detail to the drawing, 1 denotes the hammer cylinder, 2 the piston, 3 the lower hollow piston rod that extends through the bottom of the cylinder and is adapted to rest on the pile to be driven, and 4 the upper hollow piston rod that extends through a gland 5 in the cylinder cover 6. The motive fluid is supplied to the hammer through the upper piston rod 4.

As best shown by Figs. 5 and 6, the piston 2 is

cupped or recessed to house an oscillatory control valve hereinafter referred to, the recess being closed by a cover plate 7 secured in position by bolts 8 (Fig. 3). The lower end of the upper hollow piston rod 4 is secured to this cover plate, and the upper end of the lower piston rod 3 is secured in a central opening formed in the base of the piston 2.

The piston 2 itself constitutes the valve casing, to which the motive fluid is supplied by way of the upper piston rod 4, and has in its peripheral wall a series of adjacent admission and exhaust ports 9 and 10 respectively. In the embodiment illustrated there are four pairs of such ports, but the number may vary according to the size of the hammer and the port area required for its effective operation. All of the ports open through the inner surface of the peripheral wall of the piston (Figs. 2 and 2a), and each of the admission ports 9 opens to the cylinder space above the piston (Fig. 5) while each of the exhaust ports 10 opens to the cylinder space below the piston (Fig. 6).

The oscillatory control valve comprises a hub member 11 journaled in the upper end of the lower piston rod 3 and presenting, within the aforesaid valve casing, spider arms 12, and a facing member 13 slidably embracing each such arm. There are as many facing members as there are pairs of ports 9, 10, i. e., four in the illustrated embodiment. The hub member rests on a ball thrust bearing 14; if desired, a ball thrust bearing may also be interposed between the shoes and the piston cover plate 7 in case of rebound of the piston due to the hammer blows. The arcuate surface of each facing member, which in the illustrated form is pressed into fluid-tight engagement with the inner peripheral surface of the piston by the motive fluid supplied to the valve casing (the interior of the piston), has a transfer duct 13a for a purpose hereinafter described.

Operating mechanism for the oscillatory control valve comprises a cam rod 15 (Figs. 5, 6 and 9) engaging the valve member 11 and supported within the lower hollow piston rod 3, and a member 16 (Figs. 1 and 7) projecting radially from the cylinder 1 through a vertical slot 17 in the said lower piston rod into engagement with a cam groove 18 formed in the cam rod. The groove 18 presents an "admission" cam surface or ramp 20 and an "exhaust" cam surface or ramp 19 such that as the member 16 moves vertically up and down with the cylinder 1 the cam rod is turned to and fro. The upper end of the cam rod and the lower end of the valve member 11 are connected by dog teeth in engagement as appears from Figs. 4 to 6, so that the turning movements imparted to the cam rod are transmitted to the valve. The lower end of the cam rod is supported by a bush or collar 22 within the lower piston rod as shown in Fig. 1.

With the hammer cylinder or ram 1 at the bottom of its stroke (Fig. 1) and the lower piston rod 3 resting on a pile to be driven, the aforesaid oscillatory valve 11, 12, 13 is in "admission" position, the facing members 13 being disposed to uncover the admission ports 9 and cover the exhaust ports 10 (Figs. 2 and 5). If now the supply of motive fluid to the upper piston rod 4 is turned on, the fluid will pass from the valve casing, i. e. the recess in the piston 2, through the ports 9 into the cylinder space above the piston to raise the cylinder. On the upward stroke of the cylinder the member 16 engages the "ex-

haust" cam surface or ramp 19 and turns the valve to the "exhaust" position in which the transfer ducts 13a in the valve facing members 13 (see Figs. 2a and 6) connect the admission ports 9 with the exhaust ports 10 whereby the fluid in the cylinder space above the piston passes to the cylinder space below the piston and then escapes by way of outlet ports 21 provided in the lower part of the cylinder. In consequence the cylinder falls by gravity to deliver a blow on the pile. As the falling cylinder approaches the end of its stroke the member 16 engages the "admission" cam or ramp 20 and resets the valve whereupon the operative cycle is repeated automatically until the supply of motive fluid to the valve casing is turned off.

To enable the hammer to be employed for extracting piles there may, as shown in Fig. 8, be a second cam groove 18a in the cam rod having "exhaust" and "admission" cam ramps disposed at lower and higher levels respectively than in the cam groove 18 so as to bring about short upward strokes of the cylinder and cushioned downward blows.

The cam groove 18a can be brought into use by removing the member 16 (Fig. 7), turning the cam rod to bring the cam groove 18a into alignment with the vertical slot 17 in the lower piston rod 3 and then re-inserting the member 16.

Other constructional modifications may be made within the scope of the invention. For instance, the members 13 affording the valve faces may be rigidly attached to or made integral with the rest of the valve, thereby to reduce torque due to sliding friction and to enable the diameter of the valve to be reduced, if desired; the lower piston rod 3 may be externally square or oval in cross section to prevent the cylinder or ram 1 turning on the piston and to ease the stress on the member 16.

A pile driving hammer constructed as hereinbefore described offers the advantages that the valve is fully automatic in action and is at all times totally enclosed and protected from damage, and that a small movement of the cam rod is sufficient to bring about a larger movement of the valve facing members thereby to delay admission of the pressure fluid and avoid cushioning of the hammer blow. At the same time the known advantages of the type of hammer to which the invention applies are enhanced, namely, the high proportion of the total hammer weight concentrated in the cylinder or ram and economical use of the motive fluid with increased silence due to the fluid exhausting from the upper to the lower part of the cylinder. It is also evident from Fig. 1 that when the cylinder is at rest in its lower position, which is its position when "pitching" piles or when transporting the hammer, the valve operating mechanism is completely housed within the cylinder and thus fully protected from damage.

I claim:

1. A pile-driving hammer comprising, in combination, a hollow piston having upper and lower vertically extending hollow piston rods, a cylinder reciprocable relatively to the piston to form the hammer striking ram guided by the piston rods, a valve turnable within the hollow piston and having angularly spaced facing members engaging the inner surface of its peripheral wall, the said wall having admission and exhaust ports opening through the said inner surface and leading respectively to the cylinder space above and below the piston, means for supplying motive

fluid to the hollow piston through the upper hollow piston rod, and means disposed wholly below the piston to turn the valve automatically on reciprocation of the cylinder alternately to open the said admission ports to the supply of motive fluid and to the said exhaust ports.

2. A pile-driving hammer as claimed in claim 1, the said means for automatically turning the valve comprising a cam rod supported within the

lower hollow piston rod and presenting at least one cam groove with linearly spaced cam ramps corresponding respectively to admission and exhaust positions of the valve, and at least one member projecting from the cylinder through a groove in the lower piston rod into sliding engagement with the said cam groove.

NOEL GONNE BELL.
